MUD EJECTION CONTROL

Clinton C. Dyer, Bakersfield, Calif.

Application May 12, 1941, Serial No. 393,103

6 Claims. (Cl. 255—28)

This invention relates to a mud ejection control for use in the drilling of oil wells and the like, and has for one of its objects the production of a simple and efficient means for preventing the sudden ejection or expelling of mud and other material from a well, as the drill stem is being lowered into the well or hole which is filled with rotary mud, or other fluid.

A further object of this invention is the production of a simple and efficient dissolvable flow bean which is adapted to be fitted between the sections of the drill stem as the drill stem is being assembled and lowered into the hole of the well, to check and prevent the sudden expelling of mud out through the top of the drill stem, the flow bean being adapted to be dissolved after the stem is in position and when pressure is applied to the well.

Another object of this invention is the production of a simple and efficient method of controlling the ejection of mud or other fluid from the upper end of a drill stem as the stem is being assembled and lowered, and at the same time providing for a free, unobstructed passage when pressure is applied to the well.

Other objects and advantages of the present invention will appear throughout the following specification and claims.

In the drawing:

Figure 1 is a vertical sectional view through a conventional well showing a plurality of sections connected to form the stem;

Figure 2 is a side elevational view partly in section of one form of dissolvable flow bean used in connection with the present invention;

Figure 3 is a horizontal sectional view taken on line 3—3 of Figure 2;

Figure 4 is a side elevational view partly in section of a further type of flow bean;

Figure 5 is a vertical sectional view through a portion of the stem showing a still further modified type of flow bean; and

Figure 6 is an enlarged top plan view of the type of flow bean shown in Figure 5.

To form a basis for a proper understanding of the present invention attention is called to the following description of the assembly and operation of devices of a general character to which the invention relates.

Modern oil well drilling is preferably done with 50 rotary equipment. The drill bit, generally a "fish-tail," rotates in much the same manner as a carpenter's auger or a dentist's drill. The stem upon which the bit operates is hollow and is made of sections or joints of heavy steel pipe,

As the drill is lowered into the well, new joints or drill pipe are added and no metal casing is used in the hole or well except for a short distance below the surface, one type of casing being indicated at A in Figure 1. This casing A preferably comprises a large pipe having a flared collar B at its upper end which extends above the surface C of the ground and carries a mud discharge pipe D leading to a mud pit. The upper end of the casing A preferably extends above the surface C of the ground to prevent surface caving and also to prevent the entrance of surface water into the hole E.

Quite often the hole is drilled several thousand feet without the necessity of providing a casing, and in order to prevent caving of the walls of the hole is filled with heavy mud. The upper joint of the drill is conventionally termed "kelly" and is square in cross-section instead of round, but is hollow. The purpose of making the upper joints square is to facilitate the attachment thereof to the rotary machinery which bores the hole. A heavy-pressure reinforced rubber hose is attached to the top of the "kelly," and the mud is pumped into the drill pipe, indicated generally at F in Figure 1, through this hose from heavy mud pumps conveniently located. The mud is pumped down through the hollow drill stem or pipe F to the bottom of the hole through an orifice in the conventional drill bit, and this mud works its way up through the open hole surrounding the hollow drill bit and runs out through the pipe D at the surface. This continuous pumping of mud is conventionally referred to in the trade as "circulation."

As the bit becomes dulled and worn, the bit is pulled from the hole and the hollow drill stem, quite often thousands of feet in length, is fastened together at intervals with heavy threaded joints known to the trade as tool joints. When the stem is removed from the hole, these joints are detached and stand in the derrick in sections. After the bit has been removed from the hole E, the bit is replaced by a new one, and then the drill pipe is lowered by adding a section at a time until the bit finally reaches the bottom of the hole at which time the rotary drilling operation begins.

During the drilling operation, the rotary mud which has been circulated in the well or hole E becomes permeated with fragments of sand, rock and steel worn from the drill bit. The hole or well E is very little larger than the drill or stem F, and when the drill or stem is lowered into the hole E, which hole is filled with rotary

mud, quite often the mud is expelled violently through the open upper end of the drill stem F, thereby filling the derrick floor G with mud and covering the drilling machinery and clothing, as well as the drillers, with mud, and occasionally causing serious injury to the eyes of employees located nearby.

It should be borne in mind that while the drill stem F is being lowered, the "Kelly" joint is detached so that the top round joint of the drill pipe is open. The hollow in the drill stem in actual practice is from three to five inches in diameter so that a large quantity of mud or drilling fluid can be expelled as the heavy pipe descends into the hole.

With the above general description in mind, the essential features of the present invention should be quite apparent, and reference is now made to the detail features which are embodied in my invention.

By referring to the drawing, and particularly to Figure 1, it will be seen that 10 designates the "fish-tail" bit which is secured to the lower end of the lower section of the tool joint or drill collar 11, and a second tool joint or drill collar 12 is threaded upon the upper end of the joint 11. A drill pipe section 13 is connected to the joint 12 by threaded engagement and a second drill pipe section 14 is connected to the pipe section 13 by means of a coupling 15. Other sections may be added until the desired length of drill stem or pipe F is provided as a complete assembly.

A dissolvable flow bean 16 is placed between the bit 10 and the tool joint 11 and a dissolvable flow bean 17 is placed between the tool joint sections 11 and 12. A dissolvable flow bean 18 is placed between the drill pipe section 13 and the tool joint section 12, and a dissolvable flow bean 19 is placed between the drill pipe sections 13 and 14, suitable flow beans being similarly placed between each of the sections making up the drill stem F.

It is not contemplated that the application or use of all of these flow beans may be necessary in any one descent of the drill bit and drill pipe into the well. At the outset, flow beans 16, 17 or 18, or any two of them, or all three of them, may be used as occasion necessitates. If, after partial descent into the hole, these preliminary flow beans should become partially dissolved, allowing too much mud to be ejected through the top of the drill pipe then additional flow beans 19 may be added to the tool joints or connections in the drill pipe as becomes necessary.

These dissolvable flow beans are also adaptable to the lowering of other well pipe or tubing into the well.

The flow bean 18 is illustrated in detail in Figure 2, and the flow bean 18 comprises an annular collar 20 having a reduced neck 21 and a restricted central bore 22 extends longitudinally of the flow bean 18 and is preferably located in the longitudinal center of the bean 18, the bore 22 being of a relatively small diameter. The flow bean 18 is preferably formed of soft material such as lime, plaster, stucco, wood stone, plastic wood, unburned clay, low grade Portland cement, or any other similar material which will gradually dissolve in water, or is gradually dissipated by abrasion. The flow bean 18 is preferably reinforced by means of longitudinally extending metal reinforcing rods 23 of a suitable shape to conform to the contour of the bean. These flow beans illustrated and described may be inset

either in the drill collar, the drill joint or in the tool joint of the drill pipe throughout the length of the stem F, and by being inset at various places in the drilling mechanism the orifice in the drill pipe or stem F will be greatly reduced at these points from the original size to about $\frac{1}{8}$ of an inch, and this structure will permit the pipe to be lowered into the well without reducing the time required for the lowering process and at the same time provide a check to prevent the sudden overflow or gushing of the mud from the upper end of the well.

In Figure 4, there is shown a slightly modified form of the invention wherein the flow bean 15 comprises a central annular collar 24 having oppositely extending reduced necks 25 and 26, and a reduced central bore 27 projecting longitudinally of the bean. Suitable reinforcing wires or rods 28 are provided to retain the contour of the bean under normal conditions.

In Figures 5 and 6 there is shown a further modified type of the dissolvable bean and in this type the bean comprises an annular disc 29 having a plurality of reduced apertures 30 formed therein, the bean 29 being clamped between the sections 31 and 32 of the stem F.

In assembling the device, as shown in Figure 1, the collar of the bean 16 is preferably clamped between the threaded end 33 of the bit 10 and the shoulder 34 of the tool joint 11, the neck portion of the bean 16 extending up into the bore of the section 11. The annular collar of the bean 17 is preferably clamped between the threaded extension 35 of the section 11 and the shoulder 36 of the section 12. The neck portion of the bean 17 extends upwardly into the bore of the section 12. The bean 18 is reversed relative to the position of the bean 17 and the annular collar of the bean 18 is clamped between the lower end of the section 13 and the shoulder 37 of the section 12, the neck 21 of the bean 18 extending downwardly into the bore of the section 12.

For the purpose of convenience the bean illustrated in detail in Figure 4 is preferably placed between the drill pipe sections 13 and 14, the central annular collar 24 of the bean 19 is fitted between the abutting ends of the sections 13 and 14, and the oppositely extending necks 25 and 26 extend into the respective bores of the sections 13 and 14. The threaded coupling 15 connects these sections 13 and 14 together, as shown. It should be borne in mind that the dissolvable beans may be constructed as to shape to fit the assembly required, and to conform to the contour in the best possible manner to anchor the beans in position and at the same time permit the beans to dissolve or to become disintegrated under the action of pressure.

It should be borne in mind that as the stem F is being assembled and lowered into the well, the beans located between the sections remain intact, but as soon as the "Kelly" joint is attached with its pressure hose and pressure is applied by means of a powerful mud pump or pumps, the mud is pumped down through the drill stem F as the bit rotates in the bottom of the hole. This pressure is generally tremendous and may reach 2500 pounds, with the pumping of fifty barrels of mud per minute, and under this pressure the beans located between the sections and which have been inserted between the sections are cut to pieces and dissipated, thereby rendering the central bore through the structure uniform and restoring the bore to its original dimensions. These beans illustrated and described constitute a tem-

porary bushing which will dissipate after the drilling bit has been lowered to the bottom of the hole or well and it is quite important that these beans be located at various places throughout the length of the drilling equipment. These beans should remain intact until the pressure of the pump is applied, at which time the beans will be dissipated.

It should be understood that certain detail changes in the mechanical construction may be employed without departing from the spirit of the invention, so long as such changes fall within the scope of the appended claims.

Any dissolvable material comes within the claim and purpose of this invention, and any reinforcement, whether metal, fibrous or otherwise, that temporarily supports the integrity of the bean, also comes within the claim and purpose of the invention.

Having described the invention what is claimed as new is:

1. A mud ejection control for well drilling apparatus comprising a stem formed of a plurality of sections, and a dissolvable bean carried in the stem, said bean having a restricted bore to permit the gradual flow of liquid up through the stem as the stem is being lowered into position within the well, and to cause erosion of the bean and the washing out of the bean as fluid continues to flow through the sections of the stem.

2. A dissolvable flow bean of the class described comprising a dissolvable body adapted to be disintegrated under pressure, the body being shaped to be carried within a drill stem, and reinforcing means for maintaining the shape of the body under normal pressure.

3. A flow bean of the class described comprising a disc adapted to be carried within a drill stem, said disc having a plurality of restricted flow apertures, the disc being adapted to retain its formation while the stem is being lowered into a well under normal pressure, and the apertures in the bean being adapted to facilitate erosion as liquid flows through the disc to restore the diameter of the bore of the stem to normal size.
4. A method of the class described comprising assembling a string of pipes out of a plurality of pipe sections having at least one dissolvable choke, lowering the string of pipes into a well, the lowering being rapid enough to cause the string of pipes to be partially supported by liquid in the well due to restricted flow through the choke, and then washing out the dissolvable choke to form a fluid passage through the string of pipes of substantially enlarged minimum cross section.
5. A throttling device for tubular drill pipe, comprising an annular body of abradable material, means for anchoring said body within said pipe, the axial perforation through said body having a diameter substantially smaller than that of said pipe.
6. In combination, a tubular drill pipe string adapted to be lowered into a borehole and a throttling device fixedly carried within said string near the lower end thereof, said throttling device comprising an abradable annular body having an axial perforation of a diameter substantially smaller than the inside diameter of said drill pipe.

CLINTON C. DYER.
